DESIGN FOR A WET TYPE GAS PUMP

Carl Blom, Portland, Oreg., assignor to Bingham
Pump Company, Inc., Portland, Oreg., a corpo-
ration of Oregon

Application March 14, 1936, Serial No. 61,628

Term of patent 14 years

To all whom it may concern:

Be it known that I, Carl Blom, a citizen of the United States and a resident of Portland, in the county of Multnomah, State of Oregon, have invented a new, original, and ornamental Design for a Wet Type Gas Pump, of which the following is a specification, reference being had to the accompanying drawing, forming a part thereof.

The figure is a perspective elevational view of a wet type gas pump showing my new design taken from one side thereof. The other side of the pump is like the side shown.

I claim:

The ornamental design for a wet type gas pump as shown and described.

CARL BLOM.
